US00D944827S

(12) **United States Design Patent** (10) Patent No.: **US D944,827 S**
Underwood et al. (45) Date of Patent: **** Mar. 1, 2022**

(54) **DISPLAY DEVICE WITH GRAPHICAL USER INTERFACE**

8,645,463 B2 2/2014 Knight et al.
D701,227 S 3/2014 Lee
D716,339 S 10/2014 Lee
D730,383 S 5/2015 Brinda et al.
D730,386 S 5/2015 Ryan et al.
D736,247 S 8/2015 Chen et al.
D736,248 S 8/2015 Chen et al.
D746,866 S 1/2016 Memoria et al.
D753,709 S 4/2016 Kawanabe
D755,239 S 5/2016 Lee et al.
D755,814 S 5/2016 Rad et al.
D757,086 S 5/2016 Kang
D759,666 S 6/2016 Kuhn et al.
D762,671 S 8/2016 Chan et al.

(71) Applicant: **Facebook, Inc.**, Menlo Park, CA (US)

(72) Inventors: **Patrick Joseph Roark Underwood**, San Francisco, CA (US); **Geoff David Joseph Teehan**, Palo Alto, CA (US); **George Lewis Kedenburg, III**, San Francisco, CA (US); **Jason Holland**, Mountain View, CA (US)

(73) Assignee: **Facebook, Inc.**, Menlo Park, CA (US)

(Continued)

(**) Term: **15 Years**

U.S. PATENT DOCUMENTS

CLAIM

D599,366 S 9/2009 Brown et al.
D599,368 S 9/2009 Kanga et al.
D608,365 S 1/2010 Walsh et al.
D614,643 S 4/2010 Viegers et al.
D648,735 S 11/2011 Arnold et al.
D651,608 S 1/2012 Allen et al.
D664,561 S 7/2012 Gleasman et al.
D664,988 S 8/2012 Gleasman et al.
D692,456 S 10/2013 Brinda et al.
D692,915 S 11/2013 Brinda et al.
D699,744 S 2/2014 Ho Kushner et al.

DESCRIPTION

The FIGURE is a front view of a display device with graphical user interface, showing our new design. The broken lines in the figure showing a display screen, electronic device, and portions of the graphical user interface are for illustrative purposes only and form no part of the claimed design.
